UNITED STATES PATENT OFFICE.

GEORGE H. JUDIA, OF CISCO, TEXAS.

REFRIGERATOR-CAR DOOR.

1,109,071.

Patented Sept. 1, 1914.

Application filed December 12, 1913. Serial No. 806,201.

To all whom it may concern:

Be it known that I, GEORGE H. JUDIA, a citizen of the United States, residing at Cisco, in the county of Eastland and State of Texas, have invented certain new and useful Improvements in Refrigerator-Car Doors, of which the following is a specification.

My invention relates to a new and useful refrigerator car door, and particularly relates to certain improvements upon the car door covered by my United States Patent Number 1,076,984, issued October 28, 1913.

In the present practice, refrigerator cars are, as a rule, equipped with pairs of swinging doors which are objectionable in many respects but primarily because they are not sufficiently tight-fitting, and because they often cannot be fully opened if the car is alongside of a depot platform. To eliminate these objectionable features, I have provided a refrigerator car door of the sliding type, that will fit very snugly when closed, and cannot possibly be obstructed in its operation by a depot platform.

It is also my object to provide a sliding refrigerator car door which when closed may be engaged at each vertical edge by strong fastening devices that will offer a powerful resistance to any unauthorized attempt to open the door.

A feature of especial importance is the novel mechanism employed to secure the rear end of the door in its closed position, and to shift said end out of the doorway previous to opening the door.

Finally, a still further object of the invention is to provide a device of the character described that will be strong, durable, efficient and simple and comparatively inexpensive to produce, also one in which the several parts will not be likely to get out of working order.

With these and other objects in view, the invention has relation to certain novel features of construction and operation, an example of which is described in the following specification and illustrated in the accompanying drawing, wherein:

Figure 1 is a view showing in side elevation a portion of a refrigerator car equipped with my novel door, the latter being shown in its closed position. Fig. 2 is a horizontal sectional view of the same, the section being taken upon the line $\alpha-\alpha$

of Fig. 1. Fig. 3 is a bottom view of the rock-shaft and lever mechanism employed to displace the rear end of my door out of the doorway. Fig. 4 is a view showing in side elevation the lower portion of the same mechanism. Fig. 5 is a detail sectional view, showing a portion of the same mechanism, the section being taken upon the line $y-y$ of Fig. 1. Fig. 6 is a detail rear view of the parts shown in Fig. 5. Fig. 7 is a detail side view of a roller-carrying bracket supporting the rear end of my door, the rail supporting the roller being also shown. Fig. 8 is a front view of the same. Fig. 9 is a detail vertical sectional view showing the means employed to support the upper end of a rock-shaft, which through its rotation actuates the rear end of my door into or out of its closed position.

Referring now more particularly to the drawings, wherein like reference characters designate similar parts in all the figures, the numeral 1 denotes the side wall of a refrigerator car, formed with a doorway receiving a door 2. As to the material and specific construction of the door 2, no limitations need herein be made, it being understood that these features will be made consistent with the purpose of the car. In referring to the door, hereinafter, the end thereof which first approaches its door-jamb in closing will be denoted as the front end and the other as the rear end. To the top of the door, adjacent to its front and rear extremities, there are secured two upwardly projecting brackets respectively designated by the numerals 3 and 4. These brackets may have the form commonly used upon a sliding door to furnish bearings for the rollers supporting the door in its sliding travel. The rollers mounted in the brackets 3 and 4 are denoted by the numerals 5, said rollers being carried by spindles 6. The roller mounted in the rear bracket 4 is loose upon its spindle, and said bracket is formed of a sufficient width to permit the roller to undergo a certain sliding displacement upon its spindle. The rollers 5 are grooved to travel upon a rail 7, supported rigidly from the wall 1 by bolts or pins 8. The rail 7 lies above the doorway of the car and extends rearwardly a sufficient distance to permit the door to be shifted to an open position in which it will leave the doorway unobstructed.

The rear portion of the rail 7, which portion

supports the door when open, occupies a parallel relation to the wall 1, and is sufficiently spaced therefrom to support the door out of contact with the wall in approaching or leaving its open position. That portion of the rail which lies above the doorway inclines gradually inward from back to front, the forward end of the same, being directly secured to the wall 1 just in front of the doorway.

From the above description, it may be readily understood that as the door 2 is shifted from its open to its closed position, its front end will gradually approach the doorway, finally entering the same and abutting against the front door-jamb 9. To complete the operation of closing the door, the rear end thereof is manually displaced directly inward, thereby subjecting the rear roller 5 to a sliding displacement upon its spindle, since said roller will continue in engagement with the rail 7. A mechanism which causes the rear end of the door to be automatically engaged by certain fastening devices in assuming its closed position will now be described.

The rear door-jamb 10 is interiorly formed adjacent to its front edge with a vertical groove 10^a receiving a rock-shaft 11, having its upper end projecting through a plate 12 into a recess in one of the roof beams, within which recess a collar 13 is fast upon the rock-shaft. The lower end of the rock-shaft, after passing through a floor beam 14, is bent at a right angle, and pivotally connected with a lever 15. Unless supported, either mechanically or manually, the lever 15 will hang vertically as indicated in dash lines in Fig. 1. At its free end, the lever 15 is formed with a slot, which, as the lever is shifted in a horizontal plane to a forwardly pointing position, (shown in Figs. 3 and 4) will receive an arcuate bracket 16 secured to the beam 14 beneath the middle portion of the doorway. Upon the rock-shaft 11, there are mounted fast three equidistant members, each formed with a short pointed protuberance 17 and a longer curved arm 18. Upon the rear edge of the door 2, there are mounted three plates 19, respectively disposed at the same elevations as the members comprising the parts 17 and 18. Each of said plates is formed with an aperture communicating with a recess 20 behind said plate, said aperture and recess being proportioned to receive the protuberance 17 having the same elevation. When the door is open, the position of the rock-shaft 11 is such that its lower end and the two members 17 and 18 extend substantially outward from the wall 1. As the rear end of the door is being manually displaced inwardly, (after the forward end has been brought into contact with the jamb 9), the plates 19, coming into contact with the

members 18 will produce a sufficient rotation of the rock-shaft to swing the members 17 into the recesses 20. During this displacement, the lever 15 will preferably be manually held in a horizontal position so that, as the rock-shaft is turned, the bracket 16 may be inserted in the slot of said lever. To secure the door in its closed position, a lock (not shown) may be engaged with the bracket 16, after the latter has been engaged with the lever 15, or a pin 21 may be passed through the bracket 16 and sealed as shown in Fig. 4.

Upon the front edge of the door, there are mounted fast three angular brackets 22, from each of which there projects a strong pin 23. Upon the door-jamb 9, there are secured three metallic sockets 24 which extend into recesses in the jamb and are disposed at substantially the same elevation as the brackets 22. As the front end of the door comes into contact with the jamb 9, the pins 23 will project into the sockets 24, and after the door has been fully displaced into the doorway, the pins 23 will be entirely recessed in the sockets 24, securely restricting the front end of the door against outward displacement. It is preferred to bevel the lateral edges of the door toward each other from front to back, the opposite edges of the door-jambs being correspondingly beveled. The door-jambs thus form a seat upon which the door may be very firmly pressed by the lever 15 and securely held through the engagement of the lever with the bracket 16. To increase the refrigerating efficiency of a car equipped with this door, strips 25 of felt or other suitable packing material may be fastened upon the vertical edges of the door which strips when pressed between the door and jambs will render the closure air-tight.

The members 17 securely and absolutely hold the rear end of the door in its closed position as long as the lever 15 is engaged by the bracket 16. When it is desired to open the door, the lock (not shown) or pin 21 is removed from the bracket 16, and the lever 15 is swung to the rear through an angle of approximately ninety degrees. The resulting partial rotation of the rock-shaft 11 will swing the members 18 to outwardly pointing positions, forcing the rear end of the door out of the doorway, and withdrawing the members 17 from engagement with the door. After its rear end has been outwardly displaced, the door may be readily pushed or pulled to its open position. To facilitate opening and closing, a handle 26 is exteriorly mounted upon the lower portion of the door.

When the door has been shifted rearwardly a sufficient distance to clear the doorway, it will come into contact with a pair of stop brackets 27, limiting the rear-

ward motion. To prevent the door from swinging outwardly from the car, it will preferably be engaged at its lower edge by two suitably shaped brackets 28.

5 While the above-described door is especially intended for use upon refrigerator cars, it is to be understood that the construction may have various applications. Thus, for example, a door of this type will 10 be very well suited for use on cars intended to contain explosives or highly inflammable stuffs such as cotton, since the closure is so perfect as to absolutely keep out sparks from the locomotive.

15 The invention is presented as including all such modifications and changes as properly come within the scope of the following claims.

What I claim is:

20 1. In a device of the character described, the combination with a car wall formed with a doorway, of a door arranged to normally fit in the doorway, formed with a plurality of recesses in one lateral edge, means normally securing the other edge of the door 25 against outward displacement, a vertical rock-shaft mounted adjacent to the recessed edge of the door, members mounted fast upon the rock-shaft normally engaging in said recesses, and displaceable therefrom through a slight rotation of the rock-shaft, arms mounted fast upon the rock-shaft, normally 30 closely adjacent to the inside of the door, a slight rotation of the rock-shaft

serving to displace the adjacent end of the door outwardly due to the shifting of said arms, and a lever by which the rock-shaft may be manually rotated.

2. In a device of the character described, the combination with a car wall formed with a doorway, of a door arranged to normally fit in the doorway, the vertical edges of the door and doorway being so beveled that the door when closed is seated against the doorway edges, a plurality of recesses being formed in one of the vertical door edges, means normally securing the other edge of the door against outward displacement, a vertical rock-shaft mounted adjacent to the recessed edge of the door, members mounted fast upon the rock-shaft, normally engaging in said recesses, and displaceable therefrom through a slight rotation of the rock-shaft, arms fast upon the rock-shaft normally closely adjacent to the inside of the door, a 55 slight rotation of the rock-shaft serving to displace the adjacent end of the door outwardly due to the resulting shifting of said arms, and a lever, pivotally connected with the rock-shaft for manually rotating the 60 same.

In testimony whereof I have signed my name to this specification in the presence of two subscribing witnesses.

GEORGE H. JUDIA.
